UNITED STATES PATENT OFFICE.

JAMES L. THOMPSON, OF ALLEGHENY, PENNSYLVANIA.

REAMING ATTACHMENT FOR DIE-STOCKS.

SPECIFICATION forming part of Letters Patent No. 712,445, dated October 28, 1902.

Application filed April 7, 1902. Serial No. 101,757. (No model.)

To all whom it may concern:

Be it known that I, JAMES L. THOMPSON, a citizen of the United States of America, residing at Allegheny, in the county of Allegheny 5 and State of Pennsylvania, have invented certain new and useful Improvements in Reaming Attachments for Die-Stocks, of which the following is a specification, reference being had therein to the accompanying drawings.

This invention relates to certain new and useful improvements in reaming attachments for die-stocks, and has for its object the provision of novel means whereby a pipe is threaded and reamed at the same time. It is a well-known fact that when pipes have been cut a bore is formed at the end of the pipe and the inner diameter of the pipe at the end is slightly contracted. Heretofore it has been customary to first thread the pipe and afterward ream the inner face of the pipe in order to obtain a uniform diameter and a smooth inner face.

It is the object of the present invention to overcome the necessity of two operations and 25 to provide novel means whereby the threading of the pipe and the reaming thereof is accomplished by a single operation.

Another object of the present invention is to provide a device of the above-described 30 character that will be extremely simple in construction, strong, durable, comparatively inexpensive to manufacture, and highly efficient in its use.

With the above and other objects in view 35 the invention consists in the novel construction, combination, and arrangement of parts to be hereinafter more fully described, and specifically pointed out in the claim.

In describing the invention in detail reference is had to the accompanying drawings, 40 forming a part of this specification, and wherein like numerals of reference indicate like parts throughout the several views, in which—

Figure 1 is a side elevation of my improved device. Fig. 2 is a vertical sectional view of the reamer attachment. Fig. 3 is a longitudinal sectional view of a pipe and dies, showing the reamer in side elevation.

In the drawings the reference-numeral 1 45 represents the stock-die, which is of the ordinary construction, carrying handles 22. Upon said handles are secured collars 3, carrying apertured lugs 4, between which are secured 55 by means of bolts 5 arms 6. These arms ter-

minate in a central plate 7, which has formed therein a square opening. From the central plate 7 also extends arms 8, 8, having outwardly-extending supports 9, which straddle the die. A square shaft 10 extends through the square opening of the plate 7 and carries on its end the reamer 11. A collar 12, which is held in position on the shaft 10 by means of a set-screw 14, rests upon the upper face of the plate 7, and a spiral spring 15 encircles the square shaft 10 below the plate 7, and the end of the spring bears against the annular washer 16, which is also secured upon the shaft 10.

The stock-die is operated in the ordinary manner upon a pipe, as shown in Fig. 3 of the drawings, and the reamer extends into the pipe. While the dies are threading the exterior of the pipe, the reamer will ream the interior of the pipe, and also acts as a mandrel, while the operation of threading and reaming are performed simultaneously.

The many advantages obtained by the use of my improved device will be readily apparent from the foregoing description, taken in connection with the accompanying drawings.

It will be noted that various changes may be made in the details of construction without departing from the general spirit of my invention.

Having fully described my invention, what I claim as new, and desire to secure by Letters Patent, is—

The combination of a pipe-threading die-stock having handles, collars secured on the said handles, said collars being provided with apertured lugs, a bowed frame formed with a central plate arranged above the stock and having its ends detachably secured between the lugs of the said collars, arms formed integral with the said plate at diametrically opposite points and extending downwardly at right angles to the said frame, said arms having their lower ends in engagement with the die, a shaft arranged in an opening in the said central plate, a reamer on the lower end of the said shaft, and a spring interposed between the said frame and reamer.

In testimony whereof I affix my signature in the presence of two witnesses.

JAMES L. THOMPSON.
